UNITED STATES PATENT OFFICE.

CHARLES H. KEESHIN, OF NEW HAVEN, CONNECTICUT.

HOOP.

No. 923,187.

Specification of Letters Patent.

Patented June 1, 1909.

Application filed February 4, 1909. Serial No. 476,053.

To all whom it may concern:

Be it known that I, CHARLES H. KEESHIN, a citizen of the United States, residing at New Haven, in the county of New Haven 5 and State of Connecticut, have invented certain new and useful Improvements in Hoops, of which the following is a specification, reference being had therein to the accompanying drawings.

10 My invention relates to new and useful improvements in hoops, and refers more especially to toy hoops, having for its object, among other things, to produce a hoop of this character within which will be suspended the figure of a monkey or acrobat, whereby the toy will be both amusing and entertaining to children.

To these, and other ends, my invention consists in the hoop, having certain details of 20 construction and combination of parts as will be hereinafter described and more particularly pointed out in the claims.

Referring to the drawing, which represents a perspective view of my improved 25 hoop, the numeral 1 designates the hoop, and passing through the same at points substantially diametrically opposite each other is a wire loop 2, the strands of which are held apart at the center of the hoop by a cross bar 3, and loosely mounted thereon is a figure 4, 30 the arms or legs of which are designated 5 and are fixed to the strands of the loop 2.

It is apparent that as this hoop is rolled 35 the figure will swing upon the cross bar 3, giving the appearance of a moving figure within the hoop.

Modifications can be made in the construction of this device, and I would therefore have it understood that I do not limit myself to the exact construction herein shown 40 and described, but claim all that falls fairly within the spirit and scope of my invention.

Having described my invention, what I claim as new, and desire to secure by Letters 45 Patent, is:

1. In a hoop, the combination with the circular body member; of a loop extending diametrically across the same, and having a strand upon either side of said body member; a cross bar connecting the strands of said 50 loop; and a figure, portions of which are movably mounted upon said cross bar and the other portions thereof fixed to said strands.

2. In a hoop, the combination with the circular body member 1; of a loop 2 extending diametrically across the same, and having a strand upon either side thereof; a cross bar 3 fixed within said loop and connecting said strands; and a movably mounted figure 4 upon said cross bar between the strands of 60 said loop, the arms 5 of said figure being fixed to said strands; all constructed and operating substantially as shown and described.

In testimony whereof I affix my signature in presence of two witnesses.

CHARLES H. KEESHIN.
